UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SEWING-MACHINE FEEDING MECHANISM.

1,244,479.

Specification of Letters Patent. Patented Oct. 30, 1917.

Application filed March 30, 1914. Serial No. 828,185.

To all whom it may concern:

Be it known that I, ALBERT H. DE VOE, a citizen of the United States, residing at Westfield, in the county of Union and State 5 of New Jersey, have invented certain new and useful Improvements in Sewing-Machine Feeding Mechanisms, of which the following is a specification, reference being had therein to the accompanying drawings.

10 This invention has for its primary object to provide a sewing machine with an upper feeding mechanism capable of operation at high speed. It has for a further object to provide alternating presser-feet, of which 15 one may have feeding movements imparted to it, adapted to be pressed upon the work in such manner that the intensity of engagement of each with the work will be proportionate to the requirements in performing 20 their respective functions. It has for further objects to provide an advantageous operative connection between the upper feeding mechanism and the lower feeding mechanism to insure the proper advance of 25 the work in its presentation to the stitch-forming mechanism and also to provide in conjunction with the upper feeding mechanism a simple and compact ruffling or auxiliary feeding device.

30 In the preferred form of the improvement the work-engaging feet are carried by bars pivotally sustained respectively by a swinging arm mounted upon a fixed fulcrum and the laterally extending arm of a plural- 35 armed rocker-fulcrum upon said swinging arm and having a second arm operatively connected with an actuating eccentric upon the main- or driving-shaft. The bracket-arm is provided with a member formed with 40 a socket in which is fitted a plunger-pin pressed downwardly by means of a spring within said socket and with its lower end resting upon the presser-bar sustaining swinging arm adjacent its fulcrum, and in- 45 termidate the latter and the connections of the presser-bars therewith, whereby the compression of the spring with the rising and falling movements of the presser-feet is 50 comparatively slight and the spring-pressure is transmitted to the presser-feet in degrees proportionate with their individual requirements.

The small range of compression and dis-

tention of the spring permits of a substantially uniform action upon the pressure-bar 55 sustaining arm and as this may be adjusted to give the desired degree of pressure on the presser-bars, its entire action throughout a cycle of operation of the presser-lifting means is uniform and without the sluggishness and consequent inadaptability to high speeds, common to mechanisms in which the degree of compression of the spring corresponds in extent with the automatic lift of 60 the presser-feet.

65 The upper and lower feeding mechanisms comprise adjustably connected rock-shafts disposed respectively above and below the bed-plate, the former having fixed thereon a yoked arm embracing an actuating eccentric upon the main-shaft. The upper rock-shaft has a depending arm having a pivotal and sliding connection with the feeding foot to which it imparts the requisite lateral feeding movements simultaneously with 70 those of the feed-dog forming a part of the lower feeding mechanism.

75 The eccentric for imparting to the presser-feet their lifting movements has also an operative connection with a rock-shaft having an adjustable connection with a swinging bar carrying a ruffling or auxiliary feeding member by which the work may be 80 fulled in its presentation to the main feeding elements.

85 The invention will be understood by reference to the accompanying drawings, in which Figure 1 is a front side elevation, partly in section, of a sewing machine embodying the present improvements, and Fig. 90 2 is a perspective view showing the needle-actuating mechanism and a part of the feeding mechanism with the throat-plate. Fig. 3 is a rear side elevation of the machine with the bed-plate in section. Fig. 4 is a 95 perspective view of the upper feeding mechanism, and Fig. 4^a a perspective view of the fulcrum-pin sustaining the presser-foot lifter and ruffling lever. Fig. 5 is a front end elevation of the sewing machine 100 with the face plate removed and certain parts in section, and Fig. 6 a sectional elevation taken through the bracket-arm standard. Fig. 7 is a sectional plan of the upper feeding and ruffling mechanisms. Fig. 8 is 105 a perspective view of portions of the strip-

ping foot lifting and ruffling mechanisms, and Fig. 9 a similar view of the ruffling lever with the ruffling blade attached. Fig. 10 is an extended perspective view of the connection between the ruffling lever and its actuating rock-shaft arm.

Journalized in the hollow bracket-arm 1 rising from the bed-plate 2 is the main- or driving-shaft 3 provided with a well known form of crank-and-pitman connection with the needle-bar 4 carrying the needle 5 cooperating in the production of stitches with the rotary hook 6 mounted upon the shaft 7 journaled beneath the bed-plate.

Secured upon the shaft 3 by means of the set-screw 8 is the collar 9 formed at one end with the flange 10 having an undercut transverse channel in its rearward face. Loosely mounted upon the fixed collar 9 is the loose collar 11 normally pressed against the flange 10 by means of the arched spring pressure-disk 12 secured to the collar 9 by screws 13 by means of which the collar 11 is held frictionally against turning. Fitted within the channel-way of the flange 10 is the slide-plate 14 carrying the rearwardly extending feed-actuating eccentric 15 having the elongated aperture 15' embracing the shaft 3. The plate 14 has an extension 14' carrying the stud 16 which enters the cam-slot 17 in the rearward face of the loose collar 11.

The collar 11 is shown provided with the peripheral stud 18 adapted to enter an aperture 19' in the upper end of the detent-lever 19 housed within a suitable recess of the bracket-arm standard in which it is pivotally mounted by means of the screw-pin 20, a spring 21 maintaining the lever 19 pressed normally beyond the path of movement of the stud 18. Pressure by the operator upon the button 22 at the upper end of the lever 19 throws the latter inward for engagement with the stud 18 whereby the manual turning of the shaft 3 in one or the other direction will shift the collar 11 relatively to said shaft and through the action of its cam-slot 17 upon the slide-plate extension 14' shift the eccentric 15 toward or from the axis of the shaft for adjustment of its eccentricity.

In the present instance, the machine is shown provided with a well-known form of vibratory take-up arm 23 extending forwardly beyond the front wall of the bracket-arm head in the forward face of which is provided a scale bearing number designations from 1 to 6 in conjunction with which the position of the upper edge of the take-up arm in a given position of the collar 11 upon the shaft 3 serves to indicate the degree of eccentricity of the feed eccentric and the consequent length of feed for which the machine is set when the stud 18 is in engagement with the detent lever 19.

Fitted upon the eccentric 15 is the block

24 which is embraced by the yoked arm 25 of a rock-lever having a hub 26 and a second arm 27 formed in its outer portion with the slot 28. The said rock-lever is secured by means of the set-screw 29 upon the rearward 70 end of the upper feed rock-shaft 30 journaled in bearing bosses 31 and 32 upon the rear of the bracket-arm. The rock-shaft 30 has secured upon its forward end by the set-screw 33 the hub 34 of a swinging arm 35 75 having upon its forked and forwardly extending lower end alined transverse bearing bosses 36 to receive the pivotal pin 37 upon which is fulcrumed the tilting block 38 formed in its forward edge with a recess 39 80 and provided with the alined bearing bosses 40 disposed at substantially right angles with and in advance of the pivotal pin 37. Slidingly fitted within the bearing bosses 40 is the guide-pin 41 secured by means of the set-screw 42 within the apertured forward extension 43 of the feeding presser-foot shank 44 which is provided with the foot-plate 45 having the usual serrated bottom and formed in its outer face with a channel in which is secured the lower end of the swinging feed-bar 46 carrying at its upper end the lateral stud-pin 47.

The stud-pin 47 of the feed-bar enters and is fitted within the apertured boss 48 95 at the outer end of the member 49 of the swinging arm or frame 50 having a transverse apertured boss 51 fitted upon the headed fulcrum-stud 52 secured by set-screws 53 in the bearing boss 54 of the bracket-arm 100 head. The arm or frame 50 is provided about midway between the bosses 48 and 51 with the spaced and alined bosses 55 and 56 in which is fitted the pin 57.

Mounted upon the pin 57 is the hub 58 105 of a rocking member having a forwardly extending arm 59 and an axially and upwardly extending arm 60 carrying the stud-screw 61 which is embraced by the boss 62 at the outer end of the lateral arm 63 of the strap 110 64 embracing the actuating eccentric 65 upon the main shaft 3. The strap 64 is provided with a second arm 66 which has a forked and transversely apertured outer end.

An apertured boss at the outer end of the rocker-arm 59 is entered by a transverse stud-pin 67 upon an arm extending from the collar 68 secured to the upper end of the presser-bar 69. To the lower end of the bar 69 is secured by the set-screw 70 the shank 120 71 of the fabric-stripping presser-foot 72 provided with the needle-hole 73. The bar 69 is guided in its vertical movements by the bearing block 74 fitted thereto and provided with the transverse pin 75 confined by means 125 of the collar 76 within a suitable aperture in the rigid arm 77 depending from the bracket-arm head.

Formed in the rearward side of the bracket-arm head is the socket member 78 130

having applied to its threaded upper end the bushing 79 to which is fitted the plunger-pin 80 formed with an annular flange 81 normally disposed near the bottom of the socket 6 and between which and the adjacent end of the bushing 79 is interposed the pressure spring 82. The plunger-pin 80 is shown with a reduced portion extending through the bottom of the socket member and provided with 10 the loose axial pin 83 of which the tapered lower end rests in a recess 84 formed in the upper face of the swinging arm 50 about midway between the fulcrum-pin 52 and pivotal pin 57. 15 The point of engagement of the plunger-pin through the pin 83 upon the arm 50 is so close to the fulcrum of the latter that its movement is very slight in the normal operation of the member 49 50, and the degree 20 of compression of the spring 82 in the opposite extreme positions of the plunger-pin is accordingly slight, so that the action of the spring is substantially uniform throughout each cycle of operation of the machine. The 25 slight range of movement of the plunger-pin thus insures against the necessity of compression of the spring beyond its elastic limit in order that the minimum pressure may be sufficient to meet the requirements of 30 the mechanism for the high speeds for which the present improvement is particularly designed. As the leverage with which the spring acts upon the member 49 50 is small, it is evident that its strength must be proportionately large, and its pressure upon the 35 plunger-pin flange 81 may be adjusted within a wide range by means of the bushing 79 in a manner well-known. The rock-lever arm 27 carries the adjustable stud-screw 85 of well-known form 40 which passes through its slot 28 and is embraced by the apertured upper end of the link 86 having its opposite end connected beneath the bed-plate by the stud 87 with 45 the lateral arm 88 of the lower feed rock-shaft 89. This rock-shaft has the usual upright arms 90 upon and between which is mounted the cross-bar 91 of the feed-bar 92 carrying the lower feed-dog 93 and formed 50 with the fork 94 at its opposite end to embrace the stud 95 of the lateral arm 96 secured upon the forward end of the feed lift rock-shaft 97 actuated in a manner well-known. Adjustment of the feed-eccentric 55 produces a corresponding adjustment in the range of oscillation of both of the connected rock-shafts 30 and 89, whose movements may be relatively varied by adjustment of the stud-screw 85 toward and from the rock-shaft 30. 60 Tapped into the forward end of the upper feed rock-shaft 30 is the fulcrum-pin 98 formed with a hexagonal flange 99 at opposite sides of which are the bearing portions 65 100 and 101, the former having journaled thereon the hub portion of the finger-lever 102 having the eccentric presser-foot lifting cam portion 103 adapted for engagement with the roller-stud 104 mounted upon the stud-screw 105 which is tapped in the outer 70 end of the pivotal pin 57 sustained by the swinging arm 49 50. The actuation of the finger-lever serves to lift the arm 49 50 in opposition to the pressure spring 82, and with it both the feeding foot and presser-foot through the described connections. 75 The bearing portion 101 of the fulcrum-pin 98 has journaled thereon the apertured boss 106 of the swinging ruffer-blade carrying lever 107 confined in position by the 80 head of the screw 98' tapped into the outer end of the pin 98. The lever 107 is formed with the slot 108 extending lengthwise thereof and substantially in register with a slot 109 of the depending crank-arm 110 of a 85 rock-shaft 111 journaled in a depending bearing member 112 of the bracket-arm head. The rock-shaft 111 has secured upon its opposite end the hub of a lateral crank-arm 113 provided with the stud-pin 114 embraced by the split lower end of a curved link 115 whose apertured opposite end embraces a pivotal pin 116 journaled in the apertured outer end of the arm 66 of the 90 eccentric-strap 64. 95 The lever 107 is pivotally connected with the slotted crank-arm 110 by means of the shouldered screw-pin 117, the washers 118 and 119 and the nut 120, in a manner well-known, the connecting parts being adapted 100 to be clamped together in different positions upon the arm 110 relatively to the rock-shaft 111. The lever 107 has at its lower end the inverted stirrup 121 embracing the ruffling 105 blade carrying arm 122 fulcrumed at one end upon the stud-pin 123 carried by the lever 107 and provided at its opposite end with a lateral inclined ear 124 upon which is secured by means of the screws 125 the 110 shank of the ruffling or auxiliary feeding blade 126. The lever 107 has adjustably secured upon its forward edge by means of the screw 127 the slotted foot 128 of a thrust-plate 129 apertured to receive and guide the 115 upper end of the thrust-pin 130 whose tapered lower end rests in a suitable depression in the upper edge of the arm 122 and which is normally depressed by means of the spring 131 interposed between the thrust-plate 129 and a collar 132 of the pin 130. The spring 131 acts through the pin 130 to normally press the ruffling blade 126 upon the work. 120 In the use of the machine, the presser-foot having been lifted by means of the finger-lever 102, the work is introduced and the presser-feet lowered. The machine being set in motion, the feeding and stitching proceeds in the usual manner, the work be- 125 130

ing fulled in advance of the presser-foot to the required extent by proper adjustment of the running device.

In the operation of the work-engaging feet 45 and 72, the oscillatory movement of the plural-armed rocker 59-60 causes first the descent of the presser-foot 72 upon the work and then the action of the stud-pin 67 as a fulcrum for the bodily rise of the rocker in its continued turning movement under the action of the eccentric 65 and with it the pivotal pin 57 and hence of the swinging arm 49-50 with the presser-foot 45. In the retrograde oscillatory movement of the rocker, the presser-foot 45 is lowered upon the work, resting upon the lower feed-dog, and the pivotal pin 57 affords a fulcrum upon which the rocker continues its turning movement in lifting the presser-foot clear 20 of the work.

While the presser-foot engages the work as above described, its connections with the actuating eccentric 65 form a relatively unyielding structure sustaining the thrust of the pressure-spring 82 through the pivotal pin 57 whose distance from the fulcrum-pin 52 relatively to the point of application of the thrust-pin extension 83 determines the proportion of the full strength of the pressure-spring to be applied to the presser-foot.

When the presser-foot is lifted, the force of the pressure-spring becomes imposed upon the feeding foot through the stud-pin 47 at a much greater distance from the fulcrum-pin 52, and hence the effective leverage of thrust of the spring is greatly reduced, being in the present instance not more than one-half of that imposed upon the presser-foot to insure the proper stripping of the work from 40 the ascending needle in the formation of the needle-thread loops.

As regards this part of the improvement it is immaterial whether either or both the presser-feet receive other movements than 45 their rising and falling movements, a characteristic feature being the means for imparting thereto the mutually alternating lifting movements and the relative proportions of the full power of the spring applied thereto.

One of the chief characteristics of the invention is the connection of the thrust-sustaining member for the spring with the work-engaging feet in such manner that it has a materially shorter range of movement than 55 the latter so that the degree of compression of the spring is materially less than that which would correspond with the lift of the presser-feet, as in other constructions heretofore devised. Another important fea-

ture is the distribution of the spring power in such manner that a greater effective thrust is imposed upon the work-stripping presser-foot than upon the feeding foot, so that each may receive a spring-pressure only of such 65 intensity as is necessary or desirable in the

performance of its respective function. In practice, the axial socket in the thrust-sustaining plunger-pin 80 is flared slightly toward its lower end, so as to allow lateral play of the axial pin 83 in following the movements of the arm 49-50 upon its fulcrum-pin 52.

By the means described for actuating the upper and lower feed rock-shafts the connections between the actuating eccentric and the upper and lower feeding mechanisms is made simple and direct and a convenient means is provided for the relative adjustment of operative throw of the coacting feeding elements.

While the preferred embodiment of this improvement is shown and described herein, it is evident that the component parts may be materially modified both in construction and arrangement without departure 85 from the scope of the present invention.

Having thus set forth the nature of the invention, what I claim herein is:—

1. In a sewing machine, the combination with a work-feeding foot, a support therefor upon which the foot is confined against bodily movement thereon in the direction of its length, and intermittently operating lifting means for said foot, of a spring for pressing said foot upon the work, and a connection between said spring and support and comprising a thrust-receiving member for said spring; said spring having a range of movement materially shorter than that of said foot.

2. In a sewing machine, the combination with a plurality of work-engaging feet and means for imparting thereto mutually alternating lifting movements, of a spring for pressing said feet upon the work, and connections between said spring and feet and comprising a common thrust-receiving member for said spring, said spring having a range of movement shorter than that of either of said feet.

3. In a sewing machine, the combination with a feeding foot, a support therefor upon which the foot is confined against bodily movement thereon in the direction of its length, means for imparting lifting and lateral feeding movements to said support, of a pressure spring for said foot, and a connection between said spring and support comprising a thrust-sustaining member for said spring, said spring having a range of movement shorter than the lifting movement of said foot.

4. In a sewing machine, the combination with a plurality of work-engaging feet, automatically acting means for imparting thereto reciprocal lifting movements, and means for imparting to one of said feet lateral feeding movements, of a pressure spring for said feet, and connections between said spring and each of said feet comprising a

thrust-sustaining member for said spring, said spring having a smaller range of lifting movement than that of either of said feet.

5. In a sewing machine, the combination with a plurality of work-engaging feet, and means for imparting thereto mutually alternating lifting movements, of a pressure spring for said feet, and connections between said spring and each of said feet and comprising means for transmitting from the spring to said feet respectively pressures of differently diminished intensity.

6. In a sewing machine, the combination with a plurality of work-engaging feet, and means for imparting thereto mutually alternating lifting movements, of a pressure spring for said feet, a thrust-sustaining member for said spring, and independent connections between said thrust-sustaining member and said feet whereby pressures of different intensities are transmitted to the latter.

7. In a sewing machine, the combination with a plurality of work-engaging feet, and means for imparting thereto mutually alternating lifting movements, of a pressure spring for said feet, a pivotally supported thrust-sustaining member for said spring, and operative connections between said thrust-sustaining member at different distances from its pivotal support and each of said feet.

8. In a sewing machine, the combination with a plurality of work-engaging feet, and means for imparting thereto reciprocal lifting movements, of a thrust-sustaining member, a pivotal support therefor, a pressure spring engaging said member laterally of said support, and operative connections from each of said feet to said thrust-sustaining member at the opposite side of the point of application of said spring thereto from said pivotal support.

9. In a sewing machine, the combination with a plurality of work-engaging feet, and means for imparting thereto reciprocal lifting movements, of a pressure spring for said feet, a thrust-sustaining member, a pivotal support therefor, a pressure spring engaging said member laterally of said support, and operative connections from each of said feet to said thrust-sustaining member at different distances from its pivotal support and exceeding that of the point of application of the spring therefrom.

10. In a sewing machine, the combination with a plurality of work-engaging feet, of a swinging arm, a pivotal support therefor, a connection between said arm and one of said feet, a rocking member fulcrumed upon said arm intermediate its connection with said foot and its pivotal support, a connection between the other of said feet and said rocking member, means for actuating said

rocking member, and a spring applied to said arm for pressing said feet upon the work.

11. In a sewing machine, the combination with a plurality of work-engaging feet, of a swinging arm, a pivotal support therefor, a connection between said arm and one of said feet, a rocking member fulcrumed upon said arm intermediate its connection with said foot and its pivotal support, a connection between the other of said feet and said rocking member, means for actuating said rocking member, and a spring applied to said arm intermediate its pivotal support and its connections with said feet.

12. In a sewing machine, the combination with a plurality of work-engaging feet, of a swinging arm, a pivotal support therefor, a connection between said arm and one of said feet, a fulcrum-pin sustained by said swinging arm intermediate its pivotal support and the connection with said foot, a plural-armed rocker mounted upon said fulcrum-pin, a connection between one arm of said rocker and a second of said feet, a rotary actuating element, and a connection between said actuating element and another arm of said rocker.

13. In a sewing machine, the combination with a plurality of work-engaging feet, of a swinging arm, a pivotal support therefor, a connection between said arm and one of said feet, a fulcrum-pin sustained by said swinging arm intermediate its pivotal support and the connection with said foot, a plural-armed rocker mounted upon said fulcrum-pin, a connection between one arm of said rocker and a second of said feet, a rotary actuating element, a connection between said actuating element and another arm of said rocker, and lifting means applied to said fulcrum-pin whereby both feet may be lifted simultaneously.

14. In a sewing machine, the combination with a plurality of work-engaging feet, of a swinging arm, a pivotal support therefor, independent connections between said arm and said feet, lifting means connected with said arm, a plunger-pin resting upon said arm, a socket member to which said plunger-pin is fitted, and a spring housed within said socket member and bearing upon said plunger-pin.

15. In a sewing machine, the combination with the frame comprising a bed-plate and an overhanging bracket-arm, of a rotary shaft journaled in said bracket-arm, upper feeding mechanism and lower feeding mechanism disposed respectively above and below the bed-plate, a rock-shaft journaled upon the bracket-arm, a depending crank-arm thereon connected with an element of the upper feeding mechanism, a lateral crank-arm fixed upon said rock-shaft, a link directly connecting said lateral crank-arm

- and an element of the lower feeding mechanism, and a third crank-arm upon said rock-shaft operatively connected with the rotary shaft.
- 5 16. In a sewing machine, the combination with the frame comprising a bed-plate and an overhanging bracket-arm, of a rotary shaft journaled in said bracket-arm, a feed rock-shaft sustained by said bracket-arm, 10 a swinging feed-bar carrying a feeding foot sustained by said bracket-arm and provided with lifting means, an operative connection between said rock-shaft and feed-bar, feeding mechanism disposed beneath the working-plate and including a feed-dog coöperating with said feeding foot, an operative connection between said rock-shaft and the lower feeding mechanism, and an operative connection between said rotary shaft and the 15 rock-shaft independent of the latter's connections with the upper and lower feeding mechanisms.
17. In a sewing machine, the combination with the frame comprising a bed-plate and an overhanging bracket-arm, of a rotary shaft journaled in said bracket-arm, a feed-actuating element mounted thereon, a feed rock-shaft sustained by said bracket-arm, a lateral arm fixed upon said rock-shaft and recessed to embrace said actuating element from which it derives operative movements, a swinging feed-bar carrying a feeding foot sustained by said bracket-arm and provided with lifting means, an operative connection between said rock-shaft and feed-bar, feeding mechanism disposed beneath the work-plate and including a feed-dog coöperating with said feeding foot, and means including relatively adjustable parts 30 disposed exterior to said bracket-arm for connecting said lower feeding mechanism with said rock-shaft.
18. In a sewing machine, the combination with a swinging feed-bar provided with a guide element disposed lengthwise thereof and carrying a feeding foot, and means for imparting lifting movements thereto, of a feed rock-shaft, a swinging arm sustained thereby, and a block fulcrumed upon and 35 transversely of said swinging arm and pro- vided with a guide element disposed transversely to its fulcrum and fitted to that of said feed-bar.
19. In a sewing machine, the combination with a rotary shaft, upper feeding mechanism including a swinging bar carrying a feeding foot, and means for imparting lateral movements thereto, and a ruffling device comprising a swinging lever carrying a ruffling blade, of an eccentric actuating member fixed upon said shaft, a sleeve embracing the same, and independent connections between said sleeve and the feed-bar and ruffling blade carrying lever, respectively, whereby lifting movements are imparted to the former and lateral operative movements are imparted to the latter.
20. In a feeding mechanism for sewing machines, a bed-plate, a lower feed-dog, a coöperating upper feeding foot, a main driving shaft located above the bed-plate, a single actuating element on said shaft for imparting lateral feeding movements to said dog and foot, and a spring operatively arranged to press said upper feeding foot 70 downward, means for moving said foot vertically into and out of engagement with the work, said spring having a range of movement materially less than that of said foot.
21. In a feeding mechanism for sewing machines, feeding members including a lower feed-dog and a coöperating upper feeding foot, a single eccentric imparting to each of said feeding members lateral feeding movements and to one of said feeding members vertical movements, a presser-foot for stripping the fabric from the needle, and a spring operatively arranged to uniformly press said upper feeding foot and said presser-foot against the work, said spring having a range of movement materially less than that of the feet.
- In testimony whereof, I have signed my name to this specification in the presence of 95 two subscribing witnesses.
